Patented Aug. 3, 1920.

UNITED STATES PATENT OFFICE.

LEON MARTOCCI-PISCULLI, OF NEW YORK, N. Y.

MEDICATED PESSARY.

1,348,728.

Specification of Letters Patent. Patented Aug. 3, 1920.

Application filed October 8, 1919. Serial No. 329,263.

To all whom it may concern:

Be it known that I, LEON MARTOCCI-PISCULLI, a citizen of the United States, and a resident of the city of New York, borough 5 of Manhattan, in the county and State of New York, have invented new and Improved Medicated Pessaries, of which the following is a full, clear, and exact description.

It is well appreciated that pessaries of the 10 usual construction have caused complications and diseases to the generative organs, such as vaginitis and fluid discharges.

Particularly where a person has contracted venereal diseases, it is well understood by the medical profession that it would be extremely desirable to have some medium or process by means of which it would be possible to permit vaporous germicidal agents, such as formaldehyde, to act 15 upon the parts affected. This has been heretofore impossible, for the reason that it is out of the question to apply to the delicate membranes and tissues any solution which will be of sufficient strength to have a detrimental effect upon any affected tissues, 20 which would not cause extreme irritation to the membranes to which it was applied. Further, any antiseptic solution applied directly to the tissues would, as might well be 25 appreciated, wear off quickly, necessitating another application. This is to be particularly avoided, in view of the fact that an ideal condition would be one in which the action of an agent such as formaldehyde 30 might be exerted upon the affected tissue and which would also have certain provisions which would permit this action to continue uninterruptedly for a lengthy period.

With these objects in view, I have constructed a medicated pessary which is particularly adaptable for the prevention and cure of venereal diseases and which may be used as a general disinfectant and deodorizer for the vagina and uterus, chiefly in advance 35 in inoperable carcinoma and other malignant tumors which affect the vagina and uterus.

A further object of my invention is the construction of an intrauterine stem pessary 40 for anteflexion of the cervix or stenosis in the external or internal os.

A still further object of the invention is the construction of a pessary which will be free from complications and diseases produced 45 by those usually used, especially those constructed of rubber, which produce infec-

tions peculiar to the generative organs when left in position for any length of time.

Another object of the invention is the construction of a pessary which shall be entirely 60 self-contained, which may be made of any suitable material, and which will have incorporated in it means permitting an evaporable germicidal agent to be associated with it.

Other objects of my invention will appear 65 upon reference to the subsequent specification.

Reference is had to the attached sheet of drawings which illustrate practical embodiments of my invention and in which 70

Figure 1 is a cross section through the female generative organs with my pessary in applied position.

Fig. 2 is an enlarged sectional side view 75 through one of my forms of pessary.

Fig. 3 is a sectional side view of a second form of pessary.

Fig. 4 is a sectional side view of a pessary constructed similarly in all respects to the pessary illustrated in Fig. 2 with the exception that a different form of stem is applied thereto.

Fig. 5 is a sectional view taken along the lines 5—5 of Fig. 4.

Figs. 6, 7, 8 and 9 show pessaries constructed in either the manner illustrated in Figs. 2 or 3 with optional forms of stems associated therewith.

In all of these views like reference numerals designate similar parts, and the reference numeral 1 indicates a female trunk; the reference numeral 2, the urethra leading to the bladder; 3, the vagina; and 4, the uterus, the latter members having applied to them my improved form of pessary.

Referring now more particularly to the construction illustrated in Fig. 2, it will be seen that my pessary may include a stem 5 provided with a central bore 6 extending through its entire length, from which may 100 extend passages 7 at right angles terminating at the outer face of the stem.

The pessary further includes a cup 8 provided with a cover 9, which cover may be formed with an annular, downwardly-extending shoulder 10 adapted to engage the inner face of the cup 8 adjacent its upper edge to provide a tight seal.

Both the cover 9 and cup 8 are provided with a centrally-located, screw-threaded 110 opening through which is adapted to project the screw-threaded lower end 11 of the

stem 5 which is formed with passages 12 affording communication between the bore of the stem 5 and the interior of the cup 8.

- It will readily be appreciated that the cup 5 may be filled with any suitable germicidal agent, such as "Geloform," and the cover 9 applied thereto. Upon the lower end 11 of the stem 5 being now inserted through the screw-threaded openings and turned down so that the screw threads on the outer face of the same cause both the cup 8 and cover 9 to be drawn tightly against the shoulder 13 formed on the stem adjacent the upper ends of the screw threads, any possible escape of the contents of the cup 8 will be prevented, as well as preventing the displacement of the cup, although permitting the gases given off by the germicidal agent to pass through the bore 6 and against the affected parts.
- 20 Optionally, the cup may be constructed, as is illustrated in Fig. 3, with a cover and cup portion which are adapted to be clipped together as at 14, the cup being retained in applied position upon the stem 5 by means 25 of a split resilient ferrule 15 provided with a retaining washer 16.

The stem of the pessary may be varied in any number of ways without in the least departing from the scope of my invention, as 30 it is often found that the mouth of the uterus varies in size as well as in rigidity and it might, consequently, be necessary, and in usual cases quite desirable, to utilize stems of the construction illustrated in Figs. 35 4, 5, 6, 7, 8 and 9.

In these figures it will be noted that Figs. 4 and 5 illustrate a pessary which is provided with a cover constructed in the identical manner as the form illustrated in Fig. 2, 40 the same being retained in applied position by means of a tube 17 provided with the usual screw threads, passages 12, and shoulder 13. However, the upper end of the tube terminates in a reduced portion around which are 45 arranged and rigidly secured, in applied position, by means of wound wire 18, the lower ends of spring arms 19, which are retained in applied position by any suitable means, such as gelatin capsules 20, which will, after 50 the pessary has been inserted, dissolve and permit the arms 19 to snap outwardly to the position indicated in dotted lines, whereby to prevent any accidental displacement of the device as a whole.

55 Another convenient form of stem, which combines general utility with cheapness of manufacture, is illustrated in Figs. 6 and 7, in which 8 is the cup provided with a cover 9, the cover having applied to it a pair of spring arms 21 provided with integral, inwardly-struck ears 22, which may be engaged by a suitable instrument 23 until the pessary has been properly positioned so as 60 to retain the arms in their retracted position, whereupon the rod or instrument 23

may be withdrawn, permitting a separation of the arms and eliminating any danger of the pessary being accidentally displaced.

Finally, in Figs. 8 and 9 there is illustrated a form of pessary which is provided with the usual cup cover 9, from which there extends a tubular screw-threaded portion 24, terminating in spring arms 25, which may be conveniently provided with screw threads, as has been illustrated in Fig. 8, or 75 a depression, as has been shown in Fig. 9. It will be seen that in these two latter figures the spring arms are held together by means of a substance such as gelatin and are subsequently expanded and prevented from returning to their normal position by virtue of a tubular member, provided with screw threads 26, or a ridged tubular member 27, which may be moved upwardly, as aforementioned, to prevent the return of the arms 25 80 to their normal position.

It will be seen that by virtue of my improved pessary the same may be placed in applied position by a physician and that a vaporized germicidal agent will pass through 90 the passages 12 into the bore 6 of the stem 5 and into contact with the parts affected, producing the desired action. Further, it will be appreciated that any suitable germicidal agent incorporated in suitable media 95 or applied on absorbent cotton or sponge may be optionally used.

It will further be noticed that the purpose of the bore 6 and the passages 7 is not alone to permit the vapor to be introduced into the parts which are to be reached, but also to permit a free passage of the fluid into the vagina from the uterus during the menstrual period, it being noted that the fluid will readily pass from the passages 7 into 105 the bore 6 and out from the lower end of the stem 5.

Obviously, numerous modifications might be resorted to without departing from the scope of my claims.

I claim:

1. A pessary, including a stem formed with a central bore extending throughout its entire length, and a container formed with an opening, said stem being adapted to project through the container opening, said stem being provided with means permitting of a communication between the container and the bore of said stem.

2. A pessary, including a stem formed with a central bore extending throughout its entire length, and a container formed with an opening, said stem being adapted to project through the container opening, said stem being formed with openings 115 through that portion of its face enveloped by said container.

3. A pessary, including a stem, a container attached to said stem being formed with a bore and openings adapted to pro- 130

- vide a passage between said container and the atmosphere, said stem being so constructed as to permit a flow of fluid through the same and past the container.
5. 4. A pessary, including a stem formed with a bore, a container associated with such stem, such container including a cover and a cup each provided with a central opening, such stem being adapted to project through such openings and being formed with passages affording communication between the interior of said cup and the bore of the stem.
- 10

5. A pessary, including a container comprising a cup, a cover mounted upon such cup and closing the same, both the cup and cover being provided with centrally located screw-threaded openings, a stem formed with a bore, the lower end of such stem being screw-threaded and being adapted to project through the screw-threaded openings in the cup and cover, whereby to retain the latter in applied position, and means affording communication between the interior of such cup and the bore of the stem.

LEON MARTOCCI-PISCULLI.
